UNITED STATES PATENT OFFICE.

AUGUSTINE FRANK LITTLEFIELD, OF LYNN, MASSACHUSETTS, ASSIGNOR TO UNITED SHOE MACHINERY CORPORATION, OF PATERSON, NEW JERSEY, A CORPORATION OF NEW JERSEY.

SOLE.

1,382,658.

Specification of Letters Patent. Patented June 28, 1921.

Application filed April 18, 1919. Serial No. 291,101.

To all whom it may concern:

Be it known that I, AUGUSTINE F. LITTLEFIELD, a citizen of the United States, residing at Lynn, in the county of Essex and 5 State of Massachusetts, have invented certain new and useful Improvements in Soles; and I do hereby declare the following to be a full, clear, and exact description of the invention, such as will enable others skilled 10 in the art to which it appertains to make and use the same.

The present invention relates to an improvement in soles for shoes, and more particularly to the manufacture of soles having 15 a sewing rib.

The object of the invention is to produce an improved form of reinforced sole for use in the manufacture of shoes. While the invention is more especially adapted for use 20 in the manufacture of welt insoles, it may also be used in making turn soles.

In the manufacture of both types of sole named a requisite of their construction consists in a marginal sewing rib to which the 25 upper materials are attached, usually by a sewed seam. To this end an important feature of the present invention resides in the formation of a sewing rib to be attached 30 to the body portion of the sole. Preferably the reinforcement and sewing rib are integral and a further object of the invention relates to the production of a novel ribbed reinforcement. Accordingly a further feature of the invention comprises the particu- 35 lar texture of the reinforcement which includes the sewing rib.

To the accomplishment of the objects named the invention comprises the features and combinations of parts hereinafter de- 40 scribed and particularly defined in the appended claims.

In the accompanying drawings illustrating the preferred embodiment of the invention, Figure 1 is a plan of a welt insole em- 45 bodying the invention; Fig. 2 is a section on line 2—2, Fig. 1; and Fig. 3 is a dia- grammatic view showing the preferred construction of the reinforcement used in making the insole.

50 In the manufacture of welt insoles it has been the practice to use a body portion of a poor grade of leather or leatherboard and to reinforce it with canvas so as to reinforce and strengthen the body of the insole, 55 and the lip turned up from the body por-

tion. It has also been the practice to provide an insole blank or body portion with a cord stitched to the body portion to form the lip to receive the inseam, and while such an insole has gained some use, the inseam is 60 liable to distort the insole by the pull exerted on the cord. According to the present invention a strip of reinforcing material 10 is woven from a plurality of thread warps 12 and two cord warps 14 united by 65 weft threads 16 into a strip having selvage edges 18. The cords are preferably although not necessarily located lip-distant from the edges of the strip and the thread warps on the outside of the cord warps are 70 closely spaced, while the thread warps between the cord warps are widely spaced, to form strong closely woven feather portions outside the cord warps, and soft, sleazy, 75 loosely woven material between the cord warps. To use the woven strip it is slitted longitudinally on its medial line to form two pieces or strips of reinforced lip material. These strips have selvage edges 18, 80 strong feather portions 20, lip forming cords 14 securely united to the body of the reinforcing material, and soft, sleazy portions 22 inside of the lip.

This strip of reinforcing material is used 85 in making insoles by being secured to one face of the body portion 24 of an unlined insole by cement and a seam of stitches 26 with the selvage edge of the strip at the edge of the insole, and with the loose, sleazy portion of the strip inside of the lip formed 90 by the cord warp 14, so that it may be gathered together in folds which occupy little space in going around the toe of the shoe thus eliminating the necessity of cutting away portions thereof. The reinforcing strip is cheap, and is securely united to the body portion of the insole so that when the upper is sewed to the lip the stress exerted on the insole by the upper is transmitted to large areas of the insole overcom- 95 ing the liability of the latter to distortion or deformation in use.

The reinforcing strips may be woven of indefinite width and subsequently slitted if the advantage of the selvage is dispensed 105 with. Thus, the reinforcing material may be woven of thread warps and cord warps and wefts with the successive areas across the warp being feather portions, a cord, a loosely woven portion, and so on, repeated 110

across the width of the fabric. Or the fabric may be a plurality of strips like that shown in Fig. 3, arranged successively across the width of the fabric. But it is preferred 5 to make the reinforcing material in the double strip illustrated in Fig. 3 because the feather portions of the strips are provided with a selvage edge which contributes to the strength of the strip and prevents it from 10 fraying at the edges. This is of advantage because when used in a welt shoe there will be no frays extending up into the shoe at the edge of the insole which present an unsightly appearance inside the shoe, and injuriously affect its selling price. The selvage is also of advantage when used in making turn shoes as in such shoes the edge of 15 the reinforcing strip is exposed and, if frayed, even more objectionable than in welt 20 shoes.

The body 24 of the insole may be made of any suitable material such as canvas, leather-board, leather and especially inferior grades of leather, or combinations of these materials, as desired.

While the preferred form of the invention is embodied in a welt insole, the invention may also be embodied in turn soles by attaching the reinforcing strip to the edge of 30 the sole in the manner above described, and sewing the upper, wrong side out, to the lip formed by the cord, in the usual manner. When the shoe is turned the upper edge of the sole will expose the edge of the reinforcing 35 strip but this edge is usually narrow and the exposure is not therefore seriously objectionable particularly in the cheaper grade of shoes to which this invention is especially adapted. In white canvas turn 40 shoes, so far from being an objection, the strip would be a distinct advantage.

The nature and scope of the present invention having been indicated and its preferred embodiment having been described, 45 what is claimed as new, is:

1. A marginal sewing-rib of textile material for shoe soles comprising a plurality of thread-warps and a centrally located lip-forming cord-warp, the thread-warps being 50 closely spaced on one side of the cord-warp and widely spaced on the other side of the cord-warp and means for uniting the warps.

2. A ribbed reinforcing material for the margins of shoe soles having a plurality of 55 thread-warps extending from edge to edge and two large lip forming cord-warps located equidistant from the edges, the thread-warps being closely spaced outside the cord-warps and widely spaced between 60 the cord-warps and weft threads uniting the

warps and forming selvages at the edges thereof.

3. A marginal sewing-rib of textile material for shoe soles comprising a plurality of warps united by weft threads, the warps including a lip forming cord-warp and thread-warps, the thread-warps being closely spaced on one side of the cord-warp and widely spaced on the other side of the cord-warp. 65

4. A ribbed reinforcing material for the margins of shoe soles comprising a plurality of thread-warps and lip forming cord-warps united by weft threads, the thread-warps being closely spaced on one side of a given cord-warp, and widely spaced on the other side of the same cord-warp. 70

5. A ribbed material for the margins of shoe soles comprising a plurality of thread-warps including a series of lip forming cord-warps united by weft threads, the thread-warps being alternately closely and loosely spaced between adjacent pairs of cord-warps, and closely spaced on the outer sides of the end cord-warps of the series where 85 selvage edges are formed by the weft threads.

6. A ribbed reinforcing material for the margins of shoe soles comprising a plurality of thread-warps and two lip forming cord-warps united by weft threads, the thread-warps being closely spaced at the edges of the strip to form hard, strong margins, and widely spaced between the cord-warps to form a soft, easily gathered center portion. 90

7. A sole for shoes comprising a body portion and a strip of reinforcing fabric secured to the marginal portion of the sole having a cord incorporated therein lip-distant from the edge of the strip. 95

8. A sole for shoes comprising a body portion and a reinforcing textile strip secured to the marginal portion thereof provided with a selvage edge and a lip-forming cord lip-distant from the edge of the strip. 100

9. A sole for shoes comprising a body portion and a strip of reinforcing material secured to the marginal portion thereof, having a closely woven portion at the edge of the body portion of the sole, a lip-forming cord lip-distant from the edge of the sole, 110 and a loosely woven portion inside of the cord.

10. A sole for shoes comprising an unlined body portion having a lip formed thereon by securing a textile strip, having a cord incorporated therein raised from the upper surface of the strip, to the margin of one face of the sole with said cord lip-distant from the edge of the sole. 115

AUGUSTINE FRANK LITTLEFIELD.
